UNITED STATES PATENT OFFICE.

OTTO GRÜNINGER, OF NEW YORK, N. Y.

IMPROVEMENT IN BRAKE MECHANISMS.

Specification forming part of Letters Patent No. 140,700, dated July 8, 1873; application filed June 11, 1873.

To all whom it may concern:

Be it known that I, OTTO GRÜNINGER, of the city, county, and State of New York, have invented a new and useful Improvement in Brake Mechanisms; and I do hereby declare the following to be a full, clear, and exact description thereof, which will enable those skilled in the art to make and use the same, reference being had to the accompanying drawing forming part of this specification, in which drawing—

Figure 1 represents a sectional side view of my invention as applied to a locomotive-engine. Fig. 2 is a plan or top view of the same.

Similar letters indicate corresponding parts.

This invention consists in combining with a compression or steam cylinder of a locomotive or stationary steam-engine a pipe leading from the exhaust cavity of the valve, or from the exhaust-port of the valve-chest, of said cylinder into a reservoir containing water, in such a manner that, when the compression-cylinder acts as a brake, the high temperature of the compressed air or gas is reduced; further, in combining with the compression or steam cylinder of a locomotive or stationary steam-engine an air-pipe and a water-pipe in such a manner that whenever the cylinder is used for the purpose of retarding the motion of some load moved by or connected to the engine, pure air is drawn into the cylinder through one pipe, and as this air is compressed its temperature is reduced by the action of the water drawn in through the other pipe; further, in the arrangement of a pipe leading from the steam-space of the valve-chest of a compression or steam cylinder to the reservoir containing the feed-water in such a manner that the heated air and water or steam which are ejected from said compression-cylinder serve to heat the feed-water, and thereby the work expended in compressing the air or steam is stored up for future use.

Before I proceed with the description of my invention I will briefly state its object. In order to check the speed of a locomotive-engine when the same is running on a descending grade, or for the purpose of stopping the locomotive altogether, it was a common practice to reverse the slide-valves, so that the pistons of the steam-cylinders are caused to

move against the action of the steam by the momentum of the locomotive itself, and of the load which may be attached to it. By this motion of the pistons air or steam is drawn into the cylinders through the exhaust-pipe, and forced into the boiler through the steam-pipes, and, as this air or steam is compressed, its temperature is raised to a high degree, and the cylinders become highly heated. Furthermore, the air which is drawn into the cylinders, being taken from the smoke-chamber of the locomotive-boiler, is impure and liable to foul the cylinders, and if the motion of the locomotive on the descending grade continues for a long time, the compressed air which is pumped into the boiler is liable to increase the pressure in the boiler to a dangerous extent.

The object of my invention is to avoid the difficulties pointed out above, and to utilize the heat of the compressed air or steam.

In the drawing, the letter A designates the boiler of a locomotive-engine, from which steam is admitted, through pipes a a, to the steam-chests b b of the cylinders B B. The steam from both cylinders exhausts through a pipe, c, from which one branch, d, extends in the smoke-chamber or smoke-stack, while another branch, e, extends in the open atmosphere. Both these branch-pipes are provided with stop-cocks or valves, which can be opened or closed by means of suitable rods or levers from the engineer's cab. The pipe c also connects, by means of a pipe, f, with a reservoir, g, containing pure water, and this pipe can be opened or closed by means of a stop-cock, h. From the top of the steam-chests b b extends a pipe, i, from which leads a pipe, j, into the reservoir g, and the end of this pipe is, by preference, connected to a coil, k.

The reservoir g may be open or closed. If it is closed, the water in it can be heated beyond two hundred and twelve degrees.

The moment I desire to slacken the speed of the locomotive, with or without a train of cars being in full motion, I shut off the steam from the boiler, connect the valve-chamber with the reservoir of the tender by opening the stop-cock of the pipe f, close the branch d which leads from the exhaust-pipe into the

smoke-stack, and open the air-pipe *e*. All these four movements may be done either simultaneously, by the motion of one lever or crank, or separately, by having independent, or partly independent, connections to each valve or cock.

When this has been accomplished I reverse the position of the link-motion, and the result is that air and water are drawn into the cylinder and then expelled through the pipe *j* into the reservoir of the tender. During this operation the air drawn into the cylinder is compressed, and the excessive heat produced by this compression of the air is counteracted by the evaporation of the water admitted together with the air, while the steam formed by the evaporation of the water acts partly as a lubricator for the piston. The cylinder is thus saved from getting overheated, and the compressed hot air and steam, being forced directly into the feed-water, give their heat up, and the feed-water becomes heated to a high degree before it is pumped into the boiler.

The hot air and steam may be forced directly into the feed-water, or they may be made to pass through a coil situated at the bottom of the feed-water tank and opening into the atmosphere. If this pipe terminates under the water in the tank it must be provided with a check-valve to prevent the water from flowing back in said pipe.

The slide-valve must be so constructed that it will not be raised from its seat by the compressed air. This object may be effected in various ways well known to engineers, and no further description of the construction of the slide-valve is required.

In going down an incline the feed-water tank ought to be fully provided with water, and when the locomotive reaches the level, or any point of the line from which it may return, the water in the tank will be found heated to a degree corresponding to the given circumstances. On high grades my invention will work to the best advantage.

If on steep grades the water in the open tank becomes heated to the boiling-point, the locomotive ought to be made to return with an uphill train, or the tank ought to be emptied into a reservoir and filled with a fresh supply of cold water, the hot water in the reservoir being used for the supply of some engine coming uphill.

Whenever it is necessary to stop a train at intermediate stations the braking up may be effected either entirely or partly according to my invention, and in this way the work expended in braking up a train may be entirely or partly saved.

During the entire operation of braking according to my system the boiler remains intact, and the advantage of my invention over the usual systems of locomotive steam-brakes is self-evident, because by my invention the steam-cylinders are prevented from getting

overheated, and principally because the heat which is equivalent to the work expended in braking up is saved.

In the previous description I have explained my invention as applied to a locomotive-engine; but my invention can also be used with the same advantage for any stationary engine which is employed for hoisting, or, more properly speaking, for lowering, any load. In applying my invention to a hoisting-engine the mechanism must be adapted to the existing circumstances. The exhaust-pipe, which in such engines generally escapes into the open atmosphere, or into a high smoke-stack free from ashes, requires no change, but the valve-chest must be connected with the feed-water tank, as above described.

If desired, a separate compression-cylinder may be used in place of the steam-cylinder for the purpose of producing the retarding effect.

If steam is admitted to the compression-cylinder instead of air, I connect the exhaust-pipe, by means of a pipe, *l*, (shown in dotted lines in Fig. 1,) with the steam-dome, or any part of the boiler, and another pipe, *m*, leads from the boiler to the feed-water tank. The steam, after having been compressed in the cylinder, is forced back into the boiler, and, in order to prevent excessive heat in the boiler and to utilize the heat produced by the compression of the steam, I let off steam or water from the boiler, through the pipe *m*, into the feed-water tank, and at the same time I pump water from the tank back into the boiler, so as to keep the same in a normal state.

What I claim as new, and desire to secure by Letters Patent, is—

1. The arrangement of a pipe leading from the exhaust-cavity of the steam-valve, or from the exhaust-port of the valve-chest of a compression or steam cylinder, into a reservoir containing water, with a pipe leading from the steam-space of the valve-chest to said reservoir, so that when the cylinder is used as a brake it is prevented from becoming overheated by the water drawn in through said pipe and forced into said reservoir, substantially as described, for the purpose specified.

2. The combination of an air-pipe with a pipe from the exhaust-cavity of the steam-valve, or from the exhaust-port of the valve-chest of a compression or steam cylinder, into a reservoir containing water, and with a pipe leading from the steam-space of the valve-chest to said reservoir, for operation, in connection with a locomotive or stationary engine, substantially as described, for the purpose specified.

This specification signed by me this 6th day of June, 1873.

OTTO GRÜNINGER.
